[57]

ABSTRACT

A limit stop assembly for use with a tuning mechanism in a TV receiver or the like uses a pawl-lug assembly to effectuate the stop function. A rotatable disc is provided which is driven by the rotation of the coarse tuning shaft of the assembly. A pawl is movable by a cam on the disc between an inner position wherein it engages the cam on the disc and an outer position where it is disengaged from the cam. A rotatable stop lug is operably connected to the disc so as to be driven thereby. The stop lug has an extended portion located radially outwardly from the pawl when the pawl is in the inner position and normally out of the path of the movement of the pawl. However, the stop lug is movable to intersect the path of movement of the pawl and therefore prevents the pawl from moving to its outer position. This prevents further rotation of the disc and therefore the coarse tuning shaft. The stop function may, if desired, occur only after a predetermined number of revolutions of the assembly have been carried out. To effectuate this, the stop lug may advantageously be associated with one of the indicators of a digital indication system.

FIG. 7

UHF TUNER STOP MECHANISM

This application is a continuation-in-part of my co-pending application Ser. No. 386,839 filed Aug. 8, 1973, now abandoned.

The present invention relates to a stop mechanism particularly well adapted for use in conjunction with a UHF detented tuning mechanism designed to tune to a large number of communication channels, although in its broader aspect the stop mechanism is adaptable for use in other environments as well.

In some of its more generic aspects, the present invention relates to the stop mechanism disclosed in U.S. application Ser. No. 359,521 entitled "Stop Mechanism For UHF Tuner Or The Like", filed May 11, 1973, now U.S. Pat. No. 3,839,917 and assigned to the same assignee to which the instant invention is assigned.

Tuners designed when actuated to tune a receiving set such as a television receiver to a preselected one of a plurality of stations or channels are well known and take many forms. Insofar as the present invention is concerned, the precise nature of the means employed in the communications receiver itself to effect tuning to a particular reception frequency forms no part of the present invention. What this invention is directed to is the mechanism by means of which a tuning element, whatever its character, is appropriately conditioned for precise reception of a particular station or channel, and more specifically, this invention is directed to a mechanism by means of which the rotation of the mechanism is stopped at the opposite ends of the tuning spectrum. The invention is here specifically disclosed in connection with a tuner designed to effect tuning over the entire UHF band, in which there are seventy or more individual channels. To provide a device capable of tuning to any selected one of the seventy or more available UHF channels with sufficient accuracy so as to be able to distinguish in its tuning between any two adjacent channels presents many problems, both mechanical and electrical. The public has become accustomed to step-by-step TV tuning in connection with the thirteen available channels in the VHF band, and therefore expects similar tuning capability in the UHF band, but the much greater number of channels which must be tuned in the UHF band, and the very high precision of tuning which is required because of the relatively close spacing of those channels, has given rise to special new mechanical arrangements for the UHF TV tuners.

It is important to the tuner manufacturer to produce tuners of extremely small size and at an exceedingly low cost. Set manufacturers are under pressure from the consumers to produce TV receiving sets which take up as little space as possible. The TV tube itself requires an appreciable amount of space, the electrical circuitry involved in tuning also presents certain space problems, and consequently it is desired by the set manufacturers that the mechanical arrangements provided for effecting tuning from one channel to another be of minimal size. Moreover, since the sales of TV sets to the public are very competitive as to price, and since a given manufacturer produces very large numbers of receiving sets, a saving of but a few cents in cost per set, or per tuner, can represent a very appreciable amount of money when a full year's sales are taken into consideration.

The requirements for small size and low cost represent only one side of the coin. The tuner must also be sturdy and reliable, since it will be operated by the owner of a TV set many hundreds of thousands of times over the life of the set for changing from one channel to another, and any failure of the mechanical tuner portion of the receiving set will be treated by the consumer, who does not know the cause of a given malfunction but is only interested in the fact that the malfunction has occurred at all, as simply a flaw in the set as a whole, thus reflecting directly upon the reputation of the set manufacturer and affecting the ability of the manufacturer to sell a set of his manufacture to that person in the future. For comparable reasons, it is essential that the mechanical tuning arrangement be able to be operated by the user with extreme ease and with simplicity of manipulation. Hence, the structure involved must be sturdy and so constructed as to move readily and without binding.

Mechanical arrangements can be, and have been, devised capable of effecting step-by-step tuning from one TV channel to another, not only within the thirteen channel VHF spectrum, but also within the seventy channel UHF spectrum, and these prior art constructions meet the above set forth requirements to greater or lesser degrees. However, any design of the prior art had to represent a very significant compromise. Sturdiness can be achieved at the expense of size and weight. Low cost can be achieved at the expense of sturdiness. To achieve reliability of action with a small device is much more difficult than with a large device. Attempts to reduce size and weight may result in parts which are improperly supported or mounted and which therefore will tend to fail in use. Increased facility of operation may call for the use of greater number of parts or larger parts than would otherwise be the case, thus adding to size and cost. Other "trade-offs" will be apparent.

While it is theoretically possible to provide a mechanism which is continuously rotatable and which will tune through the UHF spectrum and then go back to the beginning of that spectrum and start tuning from channel to channel all over again, there are mechanical and electrical considerations which appear to make such an arrangement unfeasible. Accordingly, stop mechanisms must be provided effective at one end and the other end of the UHF spectrum. Stop mechanisms involving less than a complete rotation of the mechanism in question are common, but when seventy channels are to be tuned, and hence seventy different positions must be detented, an excessively large detent wheel is required if detenting accuracy is not to be sacrificed. Hence, multi-turn detent wheels are often employed in mechanisms of the type in question. This greatly complicates the stop problem. Stop mechanisms separate and distinct from the other functioning parts of the tuner, and connected to those parts by means of step-down gearing or the like, can be used but they add appreciably to the size and cost of the tuning assemblies.

It is a prime object of the present invention to devise a stop arrangement for a tuner which will achieve the desired objectives of reliability, sturdiness, low cost, small size, and low weight to an optimum degree with respect to all of said requirements, and with a minimum amount of sacrifice with respect to any given requirement in order to achieve required results with respect to some other requirement.

It is a more specific object of the present invention to provide a TV tuner construction in which the stop mechanism is constituted to as large a degree as possible by parts which are otherwise required in the operating mechanism.

It is an additional object of the present invention to devise a stop mechanism which, by virtue of its construction and arrangement, can be adapted to provide for effective stop action at given points in the rotation of a detent wheel while permitting that detent wheel to make a plurality of complete rotations.

It is another object of the present invention to devise a stop mechanism of the multi-turn type in which the stopping is effected at a particular point by cooperation with a pre-existing position indicator otherwise required in the operating mechanism.

Yet another object of the present invention is to provide a stop mechanism, particularly for a TV tuner construction, in which all of the active parts of the stop mechanism are sturdily and reliably mounted for long life and sure and easy rotation, yet in which parts take up a minimal amount of space and are of minimal cost.

A still further object of the present invention is to define a stop mechanism, particularly for a TV tuner assembly, the parts of which can be readily and inexpensively manufactured and assembled, thereby to produce a compact and reliable device.

In accordance with the present invention the stop function is effected by cooperation between a rotatable stop lug which is driven by the rotation of a disc connected to the coarse tuning shaft. A pawl moves radially inwardly and outwardly over a cam on the disc as the disc is rotated. The stop lug has an extended portion which is normally out of the path of the movement of the pawl. This portion is located radially outwardly from the pawl when the pawl is not in contact with the outwardly extending section of the cam. However, when the stop lug is rotated to a predetermined position, the extended portion of the stop lug intersects the path of movement of the pawl, thus preventing the pawl from moving out of the way of the cam, thereby preventing any further rotation of the disc.

Suitable means are provided to rotate the stop lug into the position where the extended portion intersects the path of the pawl when the stop function is required. These means are preferably designed to bring the stop lug into the stop position after the disc has made a predetermined number of revolutions in a given direction. The means may well comprise a portion of the position indicator which is associated with the mechanism. Preferably, the stop lug has two extended portions rotatably offset from each other such that the rotation of the detent wheel is prevented at both of the opposite ends of the channel spectrum.

In the first embodiment of the present invention the pawl comprises a detent arm and a stop arm mounted on a common shaft for simultaneous movement. The detent arm communicates with a detent wheel having a plurality of cam members or detents on the periphery thereof. As the detent wheel rotates, the detent arm moves in and out of the recesses between the detents on the wheel thus causing the stop arm to move in a similar manner. When the stop lug is positioned to prevent the stop arm from outward movement, this also prevents the detent arm from moving outward from the recess in which it lies. This prevents further rotation of the detent wheel thus accomplishing the stop function.

In the second embodiment a detent wheel and detent arm are also provided but do not participate in the stop function. The stop arm and detent arm move independently. The cam is provided on a rotatable disc which moves with the detent wheel as the tuning shaft is rotated. A cam follower in the form of a protrusion on the lower extremity of the stop arm is provided to contact the cam. Each time the disc rotates 360°, the cam contacts the protrusion moving the stop pawl outwardly. If the stop lug is in position to prevent the outward movement of the stop arm, the disc is prevented from further rotation and the stop function is accomplished. In both embodiments it is preferably that the rotatable disc upon which the cam is situated be a disc which is ordinarily incorporated into an assembly without a stop mechanism, thus limiting the number of additional parts necessary. In the first embodiment it is the conventional detent wheel which constitutes the cam. In the second it may be part of the normally provided channel numeral indicia mechanism which carries the cam.

For example, in UHF tuners where some seventy channels must be tuned, it is common to employ a digital type position indicator having one part which indicates "units" and the other part which indicates "tens". The tens part may be used to position the stop lug; indeed, the stop lug may well be defined, as is here specifically disclosed, by a portion of the tens index itself. Since the tens indicator will rotate only once for several rotations of the detent wheel, the disc utilized to effectuate this motion may be used to support the cam of the second embodiment. Thus, the stop mechanism can be advantageously associated with this portion of the assembly in order to limit the number of additional parts necessary. Several rotations of the detent wheel may therefore be permitted before the stop function is initiated.

As a result, only a minimal number of parts other than those already required in the tuning mechanism may be utilized to accomplish the desired stop function, with only minimal additional space being required over and above that utilized for the other parts of the tuning mechanism.

To the accomplishment of the above and to such other objects as may hereinafter appear, the present invention relates to the structure and arrangement of a limit stop assembly particularly well adapted for use in a TV tuner, as defined in the appended claims and as described in the specification, taken together with the accompanying drawings in which:

FIG. 1 is a side cross-sectional view of the first preferred embodiment of the present invention;

FIG. 2 is a top cross-sectional view of the embodiment of FIG. 1;

FIG. 3 is a rear cutaway view taken along line 3-3 of FIG. 1;

FIG. 4 is a cutaway view taken along line 4-4 of FIG. 1 showing the stop lug in its extreme counterclockwise position;

FIG. 5 is a view similar to that of FIG. 4 but showing the stop lug in an intermediate position and in its extreme clockwise position;

FIG. 6 is a side fragmented view of the second preferred embodiment of the present invention; and

FIG. 7 is a cutaway view taken along line 7-7 of FIG. 6.

The limit stop assembly of the present invention is specifically designed for use in UHF TV tuners, although it may be utilized in other applications. However, the tuner mechanism itself plays no part of the present invention and therefore is not illustrated. It will be understood, however, that the tuner may be constituted by a rotary variable condenser tuned transmission line or the like, provided with a shaft generally designated A which is, in effect, the output shaft of the mechanism herein disclosed, rotation of that shaft A effecting a tuning operation. The output shaft A is designed to be rotated by a coarse tuning shaft, generally designated B, the driving mechanism generally designated C operably connecting the coarse tuning shaft B to the output shaft A. The driving mechanism C includes a detent wheel, generally designated D, which rotates as the coarse tuning shaft B is rotated and which is detent-maintained in different rotational positions through the cooperation with a detent arm generally designated E. The outer surface of the detent wheel D is defined by a plurality of recesses separated by radially outwardly projecting portions.

In the first embodiment, as seen in FIGS. 1 through 5, the rotation of detent wheel D from one detented position to the next causes detent arm E to move out from and then into the recesses in a substantially radial path as it passes over the projecting cams interposed between the adjacent detent wheel recesses. As detent arm E moves, a stop arm, generally designated F, will move along with it. Detent arm E and stop arm F together form a pawl, generally designated G. Detent arm E and stop arm F are both mounted on a shaft, generally designated H, and a spring is provided to urge detent arm E into the recesses of detent wheel D.

Means, generally designated I, are provided for drivingly connecting detent wheel D to a stop lug, generally designated J. Preferably, stop lug J is provided with two extended portions which are circumferentially offset from each other. Each of these extended portions is located radially outwardly of the stop arm F when the detent arm E is situated within one of the recesses on detent wheel D but in such a position as to interfere with radially outward movement of the stop arm F when it is in registration with the stop arm F and when the detent arm E negotiates one of the cams of the detent wheel D. Normally, both of the extended portions of stop lug J are circumferentially out of registration with the path of stop arm F and therefore do not interfere with the movement thereof. As long as stop arm F is free to move, the rotation of coarse tuning shaft B is not inhibited by detent arm E. However, in two positions in the rotation of stop lug J, one for each extended portion thereof, an extended portion will intersect the path of stop arm F, thus preventing the movement thereof. In these positions the stop lug J prevents stop arm F from moving outwardly thereby preventing detent arm E from moving out of the recess on detent wheel D in which it is situated. This prevents the rotation of detent wheel D and hence of coarse tuning shaft B. Means I is designed such that the extended portions of stop lug J intersect the path of stop arm F at both of the opposite ends of the channel spectrum.

In the second embodiment the detent arm D and stop arm F, although mounted on the same shaft H, move independently. The pawl G is comprised of stop arm F alone. The cam, instead of being one of the raised portions on wheel D, is situated on a disc which is fast on

coarse tuning shaft B and which transfers the motion thereof to the channel indicia drive means I which in turn drives a tens indicator, generally designated K. A protrusion, which acts as a cam follower, is situated on the lower extremity of stop arm F. Stop arm F is moved outwardly each time the disc is rotated 360° such that the cam contacts the protrusion. If the stop lug J is in position to prevent the stop arm F from moving outwardly, no further rotation of the disc will be possible. This in turn will prevent further rotation of coarse tuning shaft B.

Preferably, stop lug J in both embodiments is operably connected to or forms a part of a tens indicator K. In this instance, means I is designed to index indicator K through a given angle each time coarse tuning shaft B is rotated through ten positions.

In addition, a fine tuning shaft, generally designated L, is operably connected to shaft A in order to provide for fine tuning. As will be described in detail below, the rotation of the fine tuning shaft L will cause the slight rotation of shaft A which is necessary to more accurately select the desired frequency.

In the first embodiment of the present invention herein disclosed, the tuner shaft A is journaled in support assembly 10 as by means of a cup-shaped bearing retainer 12 and ball bearings 14. The portion of support shaft A directly to the right of retainer 12 is recessed at 16, and the tip 18 of coarse tuning shaft B is freely received in that recess thus permitting relative rotation between the coarse tuning shaft B and tuner shaft A. Fast on coarse tuning shaft B is a collar portion 20 upon which detent wheel D is mounted. Detent wheel D extends out radially from portion 20 to an appreciable degree, and has, on the periphery thereof, a plurality of detent recesses separated by protruding portions or cams. As described herein, detent wheel D has ten recessed portions thereon. Hence, for the tuning of seventy channels such as are provided in the UHF band, the detent wheel D will have to make seven rotations. Fast on shaft H, each end of which is mounted on support 10, is detent arm E which forms a portion of pawl G. Detent arm E communicates with the periphery of detent wheel D so that as detent wheel D is rotated the arm will move in and out of the recesses thereon. Detent arm E is urged into the recesses on detent wheel D by means of a spring 22 which provides the appropriate bias on arm E.

Gear 24 is rotatably mounted on a shaft 26 which extends radially from collar 20. A normally stationary crown gear 28 is mounted on retainer 12 and meshes with gear 24. Also meshing with gear 24 is crown gear 30 which is fast on the extreme right-hand portion of tuner shaft A. As coarse tuning shaft B is rotated, gear 24 revolves about shaft B. As gear 24 revolves it meshes with crown gear 28 which is normally stationary, thus causing gear 24 to rotate. The rotation of gear 24 in turn causes crown gear 30 to rotate thus rotating tuner shaft A. In this way, the rotation of coarse tuning shaft B is transferred to tuner shaft A.

In this first embodiment pawl G comprises two elements, detent arm E and spaced therefrom, a stop arm F. Both are mounted on shaft H such that they move together. As detent arm E moves along its radial path in and out of the recesses of detent wheel D, stop arm F moves along a corresponding radial path which is parallel to but offset along the axis of shaft H from the path of detent arm E.

Stop lug J is situated immediately adjacent stop arm F. Preferably, stop lug J is mounted on or forms a part of tens indicator K. Stop lug J is driven by means I, as described below, thus causing tens indicator K to rotate accordingly.

Stop lug J is provided with a pair of extending portions, 32 and 34, rotatably offset from each other. On each of the extended portions 32 and 34 is mounted a finger 36 and 38, respectively, extending perpendicular to the plane of movement of stop lug J into the plane determined by the path of movement of adjacent stop arm F. When detent arm E is situated within one of the recesses on detent wheel D, stop arm F is situated in a position radially inward of the arc which fingers 36 and 38 define as stop lug J is rotated. When stop lug J is in a rotational position wherein neither of the fingers intersects the radial path of stop arm F, stop arm F will not be prevented from moving radially outward and therefore the stop function will not be initiated. However, when stop lug J is in a rotational position wherein either finger 36 or 38 intersects the radial path of stop arm F, as shown in FIG. 4, stop arm F will be prevented from moving radially outward. The prevention of the outward radial movement of stop arm F in turn will cause detent arm E to remain in the recess in which it is situated thus preventing the rotation of detent wheel D. The prevention of the rotation of detent wheel D will prevent the rotation of coarse tuning shaft B and therefore crown gear 30 which operably connects coarse tuning shaft B to tuner shaft A. In this way, the stop function is provided. Stop arm F has an extended nose portion 41 with an inclined upper surface. The shape of stop arm F causes it to be cammed underneath finger 36 as lug J moves in a counterclockwise position. The body portion 43 has a curved back to provide clearance for stop arm F under finger 38 as stop lug J moves in a clockwise direction. In this way the stop function will not be effectuated until the proper time but when it is, the relative positions of all of the elements in the assembly will be corrected to initiate the stop function.

Stop lug J is provided with two extended portions 32, 34, so that the rotation of coarse tuning shaft B will be limited at either end of the channel selection spectrum. Stop lug J has an intermediate portion 40 upon which are mounted a series of gear teeth 42 which mesh with gear 44 which forms a part of means I. Gear 44 is rotatably mounted on shaft 46 which is in turn mounted on support 10. Immediately adjacent stop lug J and mounted fast on coarse tuning shaft B is a disc 48 having a protrusion 50 on the periphery thereof. Protrusion 50 has a pair of gear teeth thereon which are situated to mesh with gear 44. Therefore, each time disc 48 rotates, the teeth on projection 50 will cause gear 44 to rotate through a given angle. The rotation of gear 44 will in turn cause stop lug J to rotate. Teeth 42, gear 44 and disc 48 are designed such that stop lug J will rotate from its extreme counterclockwise position (as seen in FIG. 4) to its extreme clockwise position (as seen in phantom in FIG. 5) each time coarse tuning shaft B completes seven rotations. Stop lug J will be effective to prevent the movement of stop arm F only when stop lug J is in either of the extreme positions. Therefore, the stop mechanism will only prevent the movement of detent wheel D at either end of the channel spectrum. In the intermediate positions in the channel spectrum, such as shown in FIG. 5, neither of the fingers 36 and

38 are in position to intersect the path of stop arm F and therefore movement thereof is permitted.

As mentioned previously, fine tuning shaft L is provided to more accurately condition the tuner mechanism such that the desired frequency can more precisely be selected. Fine tuning shaft L is slidably mounted within a fine tuning shaft sleeve 52 which extends perpendicular to the surface of support 10 at the extreme front (right as seen in the drawings) of the assembly. When fine tuning shaft L is depressed (moved towards the left, in the drawings) by pushing dial 74 provided for this purpose against a spring (not shown), gear 54 which forms a part thereof meshes with a gear 56 which is rotatably mounted on shaft 58 which is in turn rotatably mounted on support 10. A cam 60 is fast on the left-hand portion of shaft 58 and rotates in accordance with the rotation of gear 56. The surface of cam 60 communicates with a cam follower surface 62 located on the periphery of normally stationary crown gear 28. As can best be seen by FIG. 3, the periphery of crown gear 28 is provided with a recess 64 in order to accommodate cam 60. One side of recess 64 forms the cam follower surface 62. A second recess 66 is provided on the surface of normally stationary gear 28 to accommodate one end of spring 22. The other end of spring 22 rests against protrusion 68 which extends from the surface of detent arm E. In this way, spring 22 serves to urge cam follower surface 62 into communication with cam 60 while simultaneously urging detent arm E into the recesses on detent wheel D.

As cam 60 is rotated by the rotation of fine tuning shaft L, normally stationary crown gear 28 is rotated (a relatively small amount) against the urging of spring 22. The rotation of normally stationary crown gear 28 rotates gear 24 which in turn rotates crown gear 30. Gear 30 is operably connected to tuner shaft A and thus serves to condition tuner shaft A to more precisely select the desired frequency.

The digital-type position indicator normally used in conjunction with a tuner drive assembly of the type herein described comprises a "units" dial in the form of a transparent disc 70 (which may also act as a tuning knob) mounted on coarse tuning shaft B and a tens dial in the form of a second transparent disc 72 mounted on tens indicator K. The discs are preferably coaxial and in close proximity to each other. The units disc 70 has indicia thereon in the form of the numerals one to ten radially spaced along the surface thereof. The tens disc 72 has indicia thereon radially spaced around the surface thereof in the form of the numerals one through seven. The numerals on the units disc 70 and the numerals on the tens disc 72 are radially offset such that a viewer looking through a stationary mask (not shown) will be able to view only a single number composed of one of the numerals from each of the discs. Preferably, detent wheel D has ten recesses thereon, and means I is designed to index tens indicator K once for each complete rotation of coarse tuning shaft B. Therefore, the viewer will be able to view in succession each of the numerals representing each of the seventy channels in the UHF band as the coarse tuning shaft B is rotated seven times. Stop lug J is formed such that extending portions 32 and 34 are positioned to intersect the path of stop arm F at the opposite ends of the channel selection band. Therefore, the viewer will be unable to turn coarse tuning shaft B to a frequency corresponding to a channel lower than the lowest channel in

the UHF band and likewise will be unable to rotate coarse tuning shaft B to a frequency corresponding to a channel higher than the highest channel in the UHF band. In this way, a stop mechanism is provided for limiting the movement of the assembly at both ends of the channel selection band.

The second embodiment of the present invention, as illustrated in FIGS. 6 and 7, works in the same manner as the first with the following exceptions. In the second embodiment, pawl G is comprised only of stop arm F. Detent arm D does not participate in the stop function and moves independently of stop arm F. Stop arm F is provided with a cam follower protrusion 39 on its lower extremity. Disc 48 is provided with a cam element 51 in the same plane as protrusion 39 but in a different plane than teeth 50.

As disc 48 is rotated, cam 51 will contact protrusion 39 to move stop arm F outward. If one of the extended portions 36 or 38 of stop lug J is present to prevent the outward motion of stop arm F, further rotation of disc 48 will be prevented, thus preventing further rotation of coarse tuning shaft B in one direction. At the other end of the spectrum, the same cam 51 or a different cam (not shown) will prevent further rotation of coarse tuning shaft B in the other direction in precisely the same manner.

As will readily be appreciated, the stop function in the first embodiment can only be initiated at the "zero" units position (i.e. 10, 20, 30, 40, 50, 60 or 70). This is because it is the movement of the stop lug J to a position which prevents stop arm F from moving outward which causes the mechanism to stop. Since lug J is connected to the tens dial K to move therewith, and dial K only moves when the units mechanism is indexed from 9 to 0, the stop function can only be effectuated at this single units position. The second embodiment does not have this limitation because cam 51 can be positioned anywhere on disc 48. Thus, the stop function can be initiated at any one of the units positions, such as 68 or 76. This is a significant advantage in some applications.

Further, the second embodiment may incorporate two separate cams 51 on different portions of disc 48, one for the stop function at the lower limit and the other for the stop function at the upper limit. However, the versatility is somewhat limited because the units position of the stop at the lower limit cannot be less than the units position of the stop at the upper limit. Thus, if the possible UHF channels are numbered 14 through 79, it is not possible in the second embodiment to have the stop at 14 and 75 because as coarse tuning shaft B is rotated toward the higher channels, the cam in the "four" position of disc 48 will hit protrusion 39 before the cam in the "five" position on the seventh rotation of disc 48, thus stopping the mechanism at 74. The reverse is true for rotations of shaft B towards the lower channels. However, the second embodiment does provide greater versatility than the first because any of the units position can be selected for stops if both stops are to be at the same units position, and in some cases different units positions can be selected for each stop.

While two embodiments of the present invention have been herein specifically described, it will be apparent that many variations and modifications may be made therein. It is intended to cover all of these variations and modifications which fall within the scope of the instant invention, as defined in the following claims.

I claim:

1. A stop assembly for use with a tuning mechanism in a TV receiver or the like comprising a support, a coarse tuning shaft rotatably mounted on said support and operably connected to condition the tuner mechanism, a rotatable member operably connected to said shaft to be driven thereby and having a cam thereon with a raised section and a lowered section, a pawl movable by said cam between an inner position wherein it engages said lowered section of said cam and an outer position wherein it engages said raised section of said cam, a stop lug rotatably mounted on said support and operably connected to said disc to be rotated thereby, said lug having an extended portion located radially outwardly from said pawl when the latter is in said inner position, normally out of the path of movement of said pawl toward its said outer position but movable to intersect the said path of movement of said pawl and prevent said pawl from moving to its outer position at a predetermined point in the rotation of said disc.

2. The assembly according to claim 1 wherein said stop lug rotates about the same axis as said coarse tuning shaft.

3. The assembly according to claim 1 wherein said stop lug is mounted on said coarse tuning shaft.

4. The assembly according to claim 1 wherein said pawl comprises a detent arm and a stop arm axially spaced from one another and operably connected so that said stop arm moves in accordance with the movement of said detent arm, said stop lug intersecting the path of movement of said stop arm.

5. The assembly according to claim 4 wherein said rotatable member comprises a detent wheel mounted on said shaft and wherein said cam is a protrusion on said wheel.

6. The assembly according to claim 4 wherein said stop arm moves along a substantially radial path as said detent arm moves between said inner and outer positions, and wherein said extended portion of said stop lug moves in an arc which intersects said radial path of said stop arm.

7. The assembly according to claim 1 wherein said pawl comprises a stop arm movable independently of all other parts of said assembly.

8. The assembly according to claim 7 further comprising channel indicia means operably connected to said stop lug to be driven thereby and wherein said rotatable member comprises a drive gear for said stop lug.

9. The assembly according to claim 1 wherein said rotatable member has more than one cam thereon.

10. The assembly according to claim 1 wherein said stop lug has two extended portions, said extended portions being rotatably offset from each other.

11. The assembly according to claim 10 wherein each of said extended portions is movable to engage said pawl and retain same in said inner position.

12. The assembly according to claim 11 wherein said pawl moves along a substantially radial path as it moves between said inner and outer positions, said extended portions of said lug travel along an arc as said lug is rotated.

13. The assembly according to claim 12 wherein said stop lug is rotatable between a first position wherein one of said extended portions intersects the path of movement of said pawl, a second position wherein both of said extended portions are nonintersecting relative

to said path of movement, and a third position wherein said other extended portion intersects said path of movement.

14. The assembly according to claim 13 wherein said pawl comprises a detent arm and a stop arm axially spaced from one another and operably connected so that said stop arm moves in accordance with the movement of said detent arm, said stop lug intersecting the path of movement of said stop arm.

15. The assembly according to claim 14 wherein the operable connection between said detent wheel and said stop lug comprises a gear and wherein said stop arm engages said gear to prevent the movement thereof when said pawl is in said first position.

16. The assembly according to claim 7 wherein said rotatable member comprises a detent wheel mounted on said shaft and wherein said cam is a protrusion on said wheel.

17. The assembly according to claim 7 further comprising channel indicia means operably connected to said stop lug to be driven thereby and wherein said rotatable member comprises a drive gear for said stop lug.

18. The assembly according to claim 8 wherein said rotatable member has more than one cam thereon.

19. The assembly according to claim 7 wherein said stop lug has two extended portions, said extended portions being rotatably offset from each other.

20. The assembly according to claim 1 further comprising a pinion gear mounted on said coarse tuning shaft, a tuner mechanism conditioning gear operably connected to the tuner mechanism to condition same in accordance with the movement of said pinion gear and a normally stationary gear mounted on said support, said conditioning gear and said normally stationary gear both meshing with said pinion gear such that the rotation of said coarse tuning shaft conditions the

tuner mechanism.

21. The assembly according to claim 20 further comprising a fine tuning shaft rotatably mounted on said support, a cam rotatably mounted on said support and operably connected to said fine tuning shaft so as to be driven thereby, a cam follower mounted on said support and operably connected to the tuner mechanism to condition same in accordance with the rotation of said cam.

22. The assembly according to claim 21 wherein said cam follower is operably connected to said normally stationary gear to rotate same in accordance with the rotation of said cam for fine tuning purposes.

23. The assembly according to claim 22 wherein said resilient means is also active on said cam follower to urge same towards said cam.

24. The assembly according to claim 20 wherein said pinion gear is rotatable about an axis perpendicular to the axis of rotation of said coarse tuning shaft.

25. The assembly according to claim 24 wherein said normally stationary gear and said conditioning gear are crown gears rotatable about the same axis.

26. The assembly according to claim 20 wherein said rotatable member comprises a detent wheel mounted on said shaft and wherein said cam is a protrusion on said wheel.

27. The assembly according to claim 20 further comprising channel indicia means operably connected to said stop lug to be driven thereby and wherein said rotatable member comprises a drive gear for said stop lug.

28. The assembly according to claim 27 wherein said rotatable member has more than one cam thereon.

29. The assembly according to claim 28 wherein said stop lug has two extended portions, said extended portions being rotatably offset from each other.
